US00D682243S

(12) **United States Design Patent**
Yoo

(10) **Patent No.:** **US D682,243 S**
(45) **Date of Patent:** **** May 14, 2013**

(54) **MOBILE TERMINAL**

(75) Inventor: **Sang-Hun Yoo**, Seongnam-Si (KR)

(73) Assignee: **Samsung Electronics Co., Ltd.**,
Suwon-si (KR)

(**) Term: **14 Years**

(21) Appl. No.: **29/427,697**

(22) Filed: **Jul. 20, 2012**

(30) **Foreign Application Priority Data**

Mar. 6, 2012 (KR) 30-2012-0010564

(51) **LOC (9) Cl.** **14-03**

(52) **U.S. Cl.**

USPC ..... **D14/138 AA**

(57) **CLAIM**

The ornamental design for a mobile terminal, as shown and described.

DESCRIPTION

FIG. 1 is a front perspective view of a mobile terminal; FIG. 2 is a front view of the mobile terminal of FIG. 1; FIG. 3 is a rear view of the mobile terminal of FIG. 1; FIG. 4 is a left-side view of the mobile terminal of FIG. 1; FIG. 5 is a right-side view of the mobile terminal of FIG. 1; FIG. 6 is a top plan view of the mobile terminal of FIG. 1; and, FIG. 7 is a bottom plan view of the mobile terminal of FIG. 1. The broken lines shown in the figures that are immediately adjacent to the shaded areas and define unshaded regions, represent the bounds of the claim, while all other broken lines are directed to environment and are for illustrative purposes only; the broken lines form no part of the claimed design. The entire un-shaded keypad region at the bottom front forms no part of the claimed design.

1 Claim, 5 Drawing Sheets
